Co. LPA(57) **CLAIM**

The ornamental design for a hose storage device, as shown and described.

DESCRIPTION

FIG. 1 is a front right side slightly downward-looking perspective view of a hose storage device, as shown and described;

FIG. 2 is a front left side slightly downward-looking perspective view thereof;

FIG. 3 is a front view thereof;

FIG. 4 is a rear view thereof;

FIG. 5 is a left side view thereof;

FIG. 6 is a right side view thereof;

FIG. 7 is a rear right side slightly upward-looking perspective view thereof;

FIG. 8 is a rear left side slightly upward-looking perspective view thereof;

FIG. 9 is a top view thereof; and,

FIG. 10 is a bottom view thereof.

The broken lines represent unclaimed portions of the hose storage device, which are included for the purpose of illustrating unclaimed environmental structure only, and form no part of the claimed design.
